UNITED STATES PATENT OFFICE.

HUGH W. KIMES, OF DAYTON, OHIO, ASSIGNOR TO THE STILWELL-BIERCE & SMITH-VAILE COMPANY, OF SAME PLACE.

HYDRAULIC VALVE.

SPECIFICATION forming part of Letters Patent No. 659,031, dated October 2, 1900.

Application filed September 26, 1899. Serial No. 731,570. (No model.)

To all whom it may concern:

Be it known that I, HUGH W. KIMES, a citizen of the United States, residing at Dayton, in the county of Montgomery and State of Ohio, have invented certain new and useful Improvements in Hydraulic Valves; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to improvements in valves for controlling hydraulic presses.

In a broad sense the object of the invention is to provide a valve which will be free from the defects which are known to exist to a greater or less extent in the valves now available for hydraulic presses. These valves in many instances are used in connection with cotton-seed-oil presses, which are usually under the control of unskilled labor. Therefore 25 more or less trouble is the result, and experience has taught the builders of machinery of this character the necessity of constructing a valve which is simple, positive, efficient, and lasting under the most unfavorable conditions. In the detailed description to follow mention will be made of the valve in connection with oil-presses; but it will be borne in mind that the said valve may be employed to drive a hydraulic ram or plunger by means 30 of fluid-pressure wherever an augmenting or increasing pressure is called for.

The main feature of the invention consists in combining an automatic high-pressure valve and a low-pressure valve in such relation that the said high-pressure valve is essentially and indirectly under control of the low-pressure valve for a certain period through the medium of the press-cylinder, during which time said high-pressure valve 40 is operated automatically by the pressure from the press-cylinder to simultaneously close the low-pressure valve and admit fluid from the high-pressure pump or other source to the press-cylinder, as will be more particularly described in the following specification,

reference being made to the accompanying drawings, of which—

Figure 1 is an end elevation of the hydraulic valve hereinafter described. Fig. 2 is a vertical section thereof on the line x x of Fig. 1; 55 Fig. 3, an elevation of the high-pressure valve and a portion of the surrounding case in section; Fig. 4, an elevation and end view, respectively, of the choker or throttling device; and Fig. 5, a vertical section on the line x x of Fig. 2.

Describing the valve in detail, A designates the body or easing, which is bored substantially as shown in Fig. 2 and has a coupling-socket B for the pipe leading from the low-pressure pump. 65

B' is a coupling-socket for the pipe leading from the high-pressure pump.

B" is a coupling for the connection of the pipe through which the automatic or high-pressure valve is actuated, and B³ is a coupling-socket for connecting the discharge-pipe; B⁴, a coupling for connection with the press.

C designates a double-seating manually-operative valve which coöperates with the 75 valve-plug C' in controlling the communication of the press-passage D' with the main high and low pressure passage D. The latter passage is common to both low and high pressure valves. The low-pressure valve serves 80 to admit pressure to move the ram and apply the initial pressure to the article to be compressed and the high-pressure valve serving to apply suitable pressure to complete the operation of squeezing or compressing said 85 article. The casing A is also provided with a suitable cavity to receive the valve C and adjuncts, the adjuncts consisting of a screw-plug E and ring E', said ring forming the upper seat for the valve C. The lower side of 90 the ring E' has an annular recess, which receives a packing-ring E'', that seals the valve-chamber a. A packing-ring a' forms a seal between said ring and the plug E. The seat or ring E' has a peripheral groove b, from 95 which a series of ports c extend inwardly and communicate with the exhaust-chamber a.

The dotted circle d indicates the pipe-opening communicating with the groove b, between which and the press-passages D' com- 100

munication is established by the valve C when moved from the seat E'.

Owing to the construction of the ring or seat E', as above described, it may be placed 5 in position without any rearrangement thereof, a communication being always established between the groove b and the exhaust-chamber a through one or more of the ports c. The valve C seats on the valve-plug 10 C' when establishing communication between the press-passage D' and the exhaust-chamber a. A piston-valve F controls the duct or passage F'. Liquid entering said passage from the source of low-pressure supply raises 15 said valve and passes into the main passage D, and, raising the valve-plug C', discharges into the press-passages D'. The hydraulic ram is thus quickly raised by this pressure to a predetermined point to suit the conditions 20 of the work. At this moment high-pressure fluid is admitted through valve H on the lower end of a differential plunger. As shown in the drawings, this plunger is reduced at the valve end to provide a chamber 25 I, which is fed by the high-pressure pump. There is also a suitable chamber I' above the upper end of the plunger, which communicates with the lower chamber I through a channel I', formed in the plunger and appearing 30 in broken lines throughout the length thereof. The fluid-pressure entering chamber I passes through the channel I' to the upper chamber I and, filling said chamber, exerts pressure on the top of the plunger stem, which is sufficient to normally maintain 35 the valve H on its seat J, thereby controlling the high-pressure passages D'' and D³ during the supremacy of the pressure in chamber I'. The middle portion of the plunger is considerably increased in diameter by 40 providing it with a piston L, below which is placed a screw-plug L'. A crimp or packing ring L' is placed between the piston and said screw-plug to seal the chamber M below said 45 piston. This chamber is of suitable depth to allow the piston proper movement to raise the valve H from its seat. It will also be observed that the diameter of said chamber is something over twice that of the upper 50 chamber I', so that the pressure under the piston will exceed that on the top of the stem at a predetermined time. The chamber M is in communication with the press-cylinder by means of a pipe connected through coupling-socket B''. The upper end of the plunger is inclosed by inner and outer screw-plugs N and N' and is surrounded by a lower screw-plug N'', which serve to hold the packing-crimps O O in position. These packing-crimps 55 seal the upper and lower chambers from the central chamber M.

P designates a choker for reducing the volume and controlling the flow from the high-pressure pump. The engaging end thereof 60 is cone-shaped and seats against a bushing or seat P'. This device reduces the passage from the high-pressure passage D'' to the main pas-

sage D by means of a slit f, cut in the cone-shaped end and constituting a narrow passage to the main passage D. It will be understood that the high-pressure passage through valve H to the chamber D'' is larger than the opening f in the end of the choker. Therefore high pressure will rapidly accumulate in the passage D'' and enter the passage D³. 75 This choker is inclosed by a screw-plug P'' and packing-crimp P'. It may be withdrawn from its seat whenever it becomes necessary to cleanse the several passages, which may be done by flushing them with liquid through 80 the high-pressure valve.

The operation of the valve is briefly described as follows: Fluid entering from the source of low-pressure supply lifts the piston-valve F, passes into the main passage D, and 85 lifts the valve-plug C'. This takes place when the valve C is moved away from the valve-plug C', as shown in Fig. 2. The pressure passes through said valve-plug and enters the press-passage D' to the press-cylinder. (Not shown.) There being communication between the press-cylinder and the chamber M, as hereinbefore stated, the pressure in said cylinder and chamber being the same per a given area, when such pressure 90 attains a predetermined stage it overcomes the pressure in chamber I' exerted on the stem of the differential plunger, and said plunger is thereby raised, and the valve H is thus lifted from its seat J. The fluid admitted through said valve to the passage D³ 95 rushes into chamber D⁴ above the low-pressure piston-valve F. This pressure exceeding that below the said valve the latter is thereby closed, and the inflow of fluid from 100 the low-pressure pump is cut off. The high-pressure fluid alone enters the press-cylinder at this point, exerting the requisite pressure upon the ram to give the material the necessary compression and complete the operation. 105

Having fully described my invention, I claim—

1. In a valve for controlling hydraulic pressure, the combination with low and high pressure valves, of a main passage communicating with both of said valves, a reduced passage between said high-pressure valve and said main passage, a passage forming a communication between said reduced passage and the low-pressure valve, a communication between the press-cylinder and the high-pressure valve, whereby said high-pressure valve is opened by pressure obtained indirectly through the low-pressure valve, and means located in the main passage for throttling the 115 passage of pressure from the high-pressure valve to said main passage whereby the initial pressure from the high-pressure valve is directed to the low-pressure valve to instantaneously close said low-pressure valve upon 120 the opening of said high-pressure valve, substantially as specified.

2. In a valve mechanism for hydraulic rams, the combination of a low and a high pressure

valve, a main passage common to both of said valves, a check-valve intercepting the communications between said main passage and the passage leading to the press-cylinder, a communication between said press-cylinder and the high-pressure valve whereby said high-pressure valve is opened when the pressure in the press-cylinder reaches a predetermined stage, a reduced passage forming a communication between high-pressure valve and said main passage, a direct passage forming a communication between the said reduced passage and the low-pressure valve, and a throttling device for retarding the communication between said reduced passage and the main passage whereby the pressure from the high-pressure valve is enabled to have an effect upon the low-pressure valve to close the same instantaneously with the opening of the high-pressure valve, substantially as specified.

3. In a valve mechanism for hydraulic rams, the combination with low and high pressure valves, of a main passage communicated with by both of said valves, a check-valve interposed between said main passage and the passage leading to the press-cylinder, a communication between said press-cylinder and the high-pressure valve, whereby said high-pressure valve is opened when the pressure in said press-cylinder attains a predetermined stage, a passage D" forming a direct communication between said high-pressure valve and said main passage, a passage forming a direct communication between said passage D" and the low-pressure valve, and a throttling device interposed in said main passage between said passage D" and the low-pressure valve whereby an accumulation of high pressure between said low-pressure valve and throttling device is prevented and the high-pressure valve is enabled to act upon the low-pressure valve instantaneously with the passage of pressure from the high-pressure valve to the said passage D", substantially as described.

4. In a valve mechanism for hydraulic rams, the combination with low and high pressure valves, of a main passage communicated with by both of said valves, a check-valve interposed between said main passage and the passage leading to the press-cylinder, a manually-

operative valve coöperating with said check-valve, a communication between said press-cylinder and the high-pressure valve, whereby said high-pressure valve is opened when the pressure in said press-cylinder attains a predetermined stage, a passage D" forming a direct communication between said high-pressure valve and said main passage, a passage forming a direct communication between said passage D" and the low-pressure valve, and a throttling device interposed in said main passage between said passage D" and the low-pressure valve whereby an accumulation of high pressure between said low-pressure valve and throttling device is prevented and the high-pressure valve is enabled to act upon the low-pressure valve instantaneously with the passage of pressure from the high-pressure valve to the said passage D", substantially as described.

5. In a valve mechanism for hydraulic rams, the combination of low and high pressure passages, a main passage common to both of said passages and communicating with a passage leading to the press-cylinder, means for reducing the volume and for controlling the flow of high pressure to said main passage, the said means being located within said main passage between the high and low pressure valves, a check-valve for controlling the passage of pressure from said main passage to the passage leading to the press-cylinder, a differential valve or plunger controlling the high-pressure passage communicating with the main passage, and a direct passage forming a communication between the high-pressure valve and the low-pressure valve whereby the initial pressure admitted through said high-pressure valve will have the effect of instantaneously closing said low-pressure valve upon the admission of pressure through the high-pressure valve, substantially as specified.

In testimony whereof I affix my signature in presence of two witnesses.

HUGH W. KIMES.
